UNITED STATES PATENT OFFICE.

WILLIAM H. DEAN, OF CHICAGO, ILLINOIS.

WINDOW-CLEANER'S BRACKET.

1,266,419.

Specification of Letters Patent. Patented May 14, 1918.

Application filed January 12, 1916. Serial No. 71,735.

To all whom it may concern:

Be it known that I, WILLIAM H. DEAN, a citizen of the United States, residing at Chicago, in the county of Cook and State of Illinois, have invented new and useful Improvements in Window-Cleaners' Brackets, of which the following is a specification.

This invention is an improved window cleaner's bracket providing a frame for arrangement on the inner side of a window and a bracket arm extending outwardly from the frame and to correspondingly extend out through the window and a seat on said bracket arm to enable a person to be safely seated on the outside of the window while cleaning the same and avoid all danger of falling and being injured or killed, the object of the invention being to provide an improved device of this character which is light, cheap and simple, which may be readily carried from place to place and which may be readily arranged for use in a window.

The invention consists in the construction, combination and arrangement of devices hereinafter described and claimed.

In the accompanying drawings:

Figure 1 is an elevation of a window cleaner's bracket constructed in accordance with my invention, showing the same set up and arranged for use at a window, the window frame and a portion of the wall in which the same is located being indicated in section.

Fig. 2 is a vertical sectional view of the same showing the bracket in folded position.

Fig. 3 is a front or inner side elevation of the bracket, showing the same set up and arranged for use.

In accordance with my invention I provide a vertical frame 1 adapted for arrangement on the inner side of a window and comprising a pair of upright bars 2 and a pair of cross bars 3-4, the former near the upper ends of the bars 2 and the latter at a suitable distance from the lower ends thereof. These cross bars are rabbeted on the upright bars and are detachably secured thereto by means of bolts 5, this construction adapting the parts of the frame to be readily disassembled when desired. At the lower portions of the upright bars 2, and on the inner sides thereof, are bracing and supporting knees 6 which may be of any

form or of the form here shown. The bars 2 are provided on their inner sides, near their upper ends, with bearings 8 for the pivot portions 9 of a pair of hooks 10, these hooks being adapted to engage on the outer side of the wall at the upper side of the window and their pivot portions being connected by an eccentrically arranged rod 11 which has an arm 12. A cord 13 is attached to this arm and a pull on this cord serves to turn the hooks into engagement with the upper part of the window.

Bearings 14 are also secured on the inner sides of the bars 2 at a point a suitable distance from their lower ends. A rock shaft 15 is mounted in these bearings and has hooks 16 to engage on the outer side of the wall, at the sill or base of the window frame and is also provided with an operating arm 17 by means of which said rock shaft may be readily turned to move said hooks 16 to engaged or disengaged position. The frame 1 is sufficiently long to extend from the floor to a point above the window so that the frame can bear against the wall, on the inner side thereof, but the width of the frame is less than that of the window and the frame may be arranged either in the center of the window or adjusted to either side thereof as desired.

A bracket 18 which is substantially U-shaped and is preferably made of iron or other metal has its arms 19 pivotally connected to the inner sides of the upright bars 2 of the frame by means of pivot bolts 20. This bracket is hence adapted to be arranged in a horizontal position extended out from the window and to bear on the base thereof or the bracket may be turned upwardly and arranged close to the frame 1 to compactly dispose the device for portage from window to window or place to place. At the outer end of the bracket is a seat 21 on which the window cleaner may sit in safety while cleaning the outside of the window and the arms of the bracket are provided with downwardly extending clamping arms 22 to bear against the outer side of the window sill.

My improved window cleaner's bracket may be made of any suitable size and of any suitable material. It is light, strong and cheap and may be readily carried from place to place and set up and used. Its use ob-

viates all danger of falling and makes it entirely safe to clean windows of tall buildings on the outside.

Having thus described my invention, I claim:

In a device of the class described, a frame for arrangement vertically on the inner side of a window, a bracket carried by the frame to project out through the window, a rock shaft mounted in bearings on the frame,

hooks on the rock shaft to engage on the outer side of the wall and a lever to turn said rock shaft to engage or disengage the hooks.

In testimony whereof I affix my signature 15 in presence of two witnesses.

WILLIAM H. DEAN.

Witnesses:

E. L. McMICKEN,
Wm. T. SULLIVAN.
